CENTRIFUGAL CASTING

Harry G. Specht, Montclair, N. J.

Application June 18, 1943, Serial No. 491,305

11 Claims. (Cl. 22—65)

1

The present invention relates to centrifugal casting, and particularly a casting machine for the production by centrifugal casting of ingots, bars, and specially shaped metal bodies, such as may be used for a particular purpose, as for instance, for producing gun barrels. Centrifugal casting produces a metal structure having many advantages, such as fine grain, uniformity, density, freedom from voids, and purity. This last advantage is characteristic of centrifugal casting, due to the fact that the pure metal may be directed outwardly in the moulds through centrifugal force, while the dross or impure metal, foreign matter, and scum, collects at the inner periphery of the centrifugally cast metal, so that this segregated impure material in the form of a thin layer may be readily removed from the body of the metal with a minimum waste. Difficulty has been experienced in the past in providing a centrifugal casting machine wherein the moulds will effectually withstand the expansion and contraction, resulting from the introduction into the moulds of the hot molten metal, without permanent distortion or cracking. Another difficulty has been experienced in the cooling of the moulds to prevent retention of heat transferred to the moulds from the molten metal that would be in excess of the critical temperature of the metal. Attempts to meet this cooling problem have consisted in the use of cooling fluids, air, fins and other such means, but these have been unsuccessful for the most part, due to complication of structure and increased tendency of the moulds to distort and crack.

It is an object of the present invention to provide a centrifugal casting machine wherein the moulds are free to expand from a cold temperature to a hot temperature, without permanent distortion or cracking, and wherein the moulds will be effectually cooled during the centrifugal casting process. It is pointed out by way of example, that in pouring certain metals above 2000 degrees, it is necessary to cool the moulds down to approximately 600 degrees, so that the net temperature of the moulds after the metal is poured into them will not be greater than the critical temperature of the metal or approximately 1400 degrees.

It is proposed in the present invention to provide a centrifugal casting machine having sectional moulds, one mould being provided for each ingot, bar, or the like, and wherein expansion and contraction may take place within the individual moulds in all directions without impos-

2

ing distortion or cracking forces upon the individual or associated moulds.

It is further proposed to provide an individual mould structure having a wall of substantially uniform thickness, so that there is a substantially uniform transfer of heat, and furthermore to provide an exposed surface, subject to the cooling effect of air during the rotation of the moulds, which is substantially proportional to the mould cavity surface, the external shape of the mould being shaped to correspond substantially to the internal cavity shape.

A further object is to provide a moulding machine wherein the moulds may be conveniently assembled or disassembled, either entirely or individually, the arrangement permitting removal and replacement of any individual mould desired.

Another object is to facilitate the removal of the moulded pieces, the arrangement permitting individual pieces to be removed if desired without removal of the mould from the machine.

Another object is to provide a centrifugal casting machine wherein the individual moulds are such that an adequate chilling ratio may be maintained between the molten metal to be poured into the moulds and the moulds themselves, it being pointed out that from a practical standpoint this ratio should be approximately from 3 to 1, 5 to 1.

A further object is to provide a centrifugal casting machine of relatively large capacity, wherein the mould units are so arranged with respect to the axis of rotation that dynamic balance may be maintained during the operation of the mould, and whereby relatively high speed may be attained both from the standpoint of centrifugal force upon the metal and cooling action upon the moulds, it being pointed out that in practice the surface speed of the moulds, according to the invention, may be about 4000 R. P. M.

It is a further object to provide a centrifugal casting machine which will permit the effective removal of gases that collect during the pouring operation, and to this end it is proposed to provide a centrifugal casting machine wherein the moulds revolve around a horizontal axis, and wherein the pouring space is disposed longitudinally of the axis and centrally of the mould units disposed circumferentially about the axis.

With the above and other objects in view, an embodiment of the invention is shown in the accompanying drawings, and this embodiment will be hereinafter more fully described with refer-

ence thereto, and the invention will be finally pointed out in the claims.

In the drawings—

Fig. 1 is a side elevation of a centrifugal casting machine, according to the exemplary illustrated embodiment of the invention.

Fig. 2 is an end elevation.

Fig. 3 is a side elevation of the mould mounting cage member, removed from the machine.

Fig. 4 is an end elevation thereof.

Fig. 5 is a longitudinal vertical sectional view of the cage and mould assembly, removed from the machine, this view being taken along the line 5—5 of Fig. 6.

Fig. 6 is a transverse vertical sectional view, taken along the line 6—6 of Fig. 5.

Fig. 7 is a vertical longitudinal sectional view, taken along the line 7—7 of Fig. 6.

Fig. 8 is a top plan view of one of the individual moulds.

Fig. 9 is a bottom plan view.

Fig. 10 is a side elevation thereof.

Fig. 11 is a plan view of the two parts of the mould shown in open position, and with the cast piece in one of the parts.

Fig. 12 is a side elevation of the cast piece removed from the mould.

Fig. 13 is an end view thereof.

Fig. 14 is a side elevation of the cast piece after removal of the longitudinal rib containing impurities.

Fig. 15 is an end view thereof.

Fig. 16 is a transverse vertical sectional view of a mould assembly according to the invention wherein the individual moulds are of different forms, to produce a variety of cross sectional shapes.

Similar reference characters indicate corresponding parts throughout the several figures of the drawings.

Referring to the drawings the centrifugal casting machine, according to the illustrated exemplary embodiment of the invention, comprises a rotatable mould carrying cage member consisting of a plurality of circumferential track rings 10, two such rings being employed in the illustrated embodiment, and to the inner peripheries of which are secured, by welding or other suitable methods, a series of longitudinally extending spaced radially disposed bars 11, the inner longitudinal surfaces 12 of which are slightly tapered from end to end, so that these surfaces diverge toward the entrance end of the cage to facilitate insertion and removal of the moulds, as will presently more fully appear.

In the operation of the machine the cage is horizontally disposed within a supporting power unit, which rotates the cage and the moulds carried thereby about a horizontal axis. This unit comprises a pair of bearing frames 13—13, which are of inverted U-form and are each provided upon the horizontal bases of each of the side legs with bearing standards 14, which constitute bearing supports for drive shafts 15—15, in addition to the bearing supports provided for these shafts in the side legs. Upon the shafts 15, between the side legs and the bearing standards 14, there are provided flanged pulley wheels 16 which engage and support the track rings 10 of the cage, the axes of the shafts 15 being disposed in planes radial to the axis of the cage and disposed at angles of substantially 90° to each other. The shafts 15 are driven from a motor 17 provided with pulleys 18 and 19 connected by belts 20 and 21 to pulleys 22 and 23 provided

respectively upon the ends of the shafts 15—15.

Idler pulleys 24 engage the track rings 10 at their upper sides, these pulleys being mounted upon shafts 25—25 journaled in slide bearings 26 disposed in slideways 27 provided at the upper corners of the frames these slideways being disposed in planes radial to the axis of the cage and disposed at angles of substantially 90° to each other and to the radial planes of the shafts 15—15. Support screws 28 carried by the frame engage the lower ends of the bearing blocks 26 and are normally adjusted inwardly so that the pulleys ride freely upon the tracks 10. By adjustment of these screws outwardly the bearing blocks 26 may be moved outwardly in the slideways 27, to raise the idler pulleys to disengage them from the tracks 10, and also to provide sufficient clearance for the tracks to be disengaged from the drive pulleys 18 by raising the cage vertically, for the purpose of convenient engagement and disengagement of the cage with respect to the drive unit. The operation may be conveniently carried out by overhead crane, or by a suitable elevating dolly wheeled beneath the cage.

The mould units are of segmental form and correspond in number to the supporting bars 11 of the cage, one unit being disposed between each bar, and each bar providing an outwardly disposed support for the adjacent marginal edges of two of the adjacent mould units. Each mould unit comprises a pair of complementary mould parts 29 having a longitudinally extending mould cavity 30 shaped to form half of the moulded piece. In the illustrated embodiment the moulded piece is shown by way of example as a circular cross-section tapered bar, such as might be used in forming a gun barrel. In this case the cavities 30 are tapered and this taper preferably corresponds to the taper of the surfaces 12 of the bars 11. The outer wall surface of the mould is concentric to the mould cavities and terminates at each side in a longitudinally extending shoulder ledge 31 adapted to seat upon the inner surface 12 of the bar 11 of the cage, the side surfaces of the mould unit being disposed in radial planes intersecting the central planes of the bars 11 which support it at each side. The cross sectional shape of the separate mould units is of substantially key-stone form, so that when the several units are assembled in concentric relation within the cage each unit is supported by the adjacent units. Their inner peripheral surfaces are concavely curved, so that the inner periphery of the assembled units is cylindrical and concentric to the axis of the cage. Extending longitudinally of the inner periphery of each mould unit is a slot 32 formed by complementary recesses in the inner side surfaces of each of the mould parts, spacer lugs 33 being provided at each end of the slot to maintain the spaced relation of its side walls and so that the two parts of the mould will not collapse toward each other. In each of the side surfaces of the moulds there are provided longitudinally extending grooves 34 for receiving tie rods for maintaining the assembled relation of the moulds within the cage, as will presently more fully appear.

The moulds are slightly longer than the bars 11 of the cage, so that they project at each end for the purpose of mounting thereon the closure end plates 35—35, these end plates being in the form of centrally apertured rings having outer and inner peripheral flanges 36 and 37 between which the ends of the mould units are positioned.

The two end plates are tied together by a series of tie rods 38, disposed in the grooves 34 of the mould units, and engaged at their threaded ends through suitable holes in the end plates where they are secured by nuts 39. In the assembled relation of the mould units and end plates the outer peripheral flanges 36 of the end plates are in opposed relation to the ends of the bars 11, so as to position the assembled mould units against relative longitudinal movement, this opposed relation being such however that the end plates may be tightly secured upon the ends of the mould units without interference from the bars 11.

The bars 11 support the assembled mould units along the shoulder ledges 31 against the outward centrifugal force of the rotating cage, but the arrangement provides for complete expansion and contraction movement of the mould units radially, circumferentially and longitudinally. It will be noted that the open form of the cage and the marginal edge support of the units therein allows unrestricted expansion and contraction radially, the slotted form of the units permits circumferential expansion and contraction to take place entirely within each unit, and the disposition of the closure end plates beyond the ends of the cage permits free longitudinal expansion and contraction. The disposition of the tie rods within the recesses 34 in the side walls of the mould units is also a factor in the complete freedom of expansion and contraction movement, as heat transfer to these tie rods will be sufficient to cause them to expand and contract in substantial conformation with the expansion and contraction of the mould units themselves.

In operation, the assembled mould units in the rotatable cage are mounted in the power unit, as shown in Figs. 1 and 2, and rotation is imparted thereto at the desired speed to create necessary centrifugal force. The molten metal is introduced into the mould through the central passage therethrough by any suitable feed means, the centrifugal force causing the metal to move outwardly in the moulds and to build up therein under centrifugal force until the moulds are completely charged, this point being predetermined, so that the mould cavities are completely filled and the metal extends partially inwardly in the entrance slots.

Due to the horizontal arrangement of the mould with its longitudinally extending mould cavities, slots, and central passage glass that form may readily escape without being trapped. The complete symmetry of the mould, and the equal support afforded by the drive pulleys, establishes dynamic balance so that relatively high rotational speed may be attained, without creating excess strain upon any of the parts.

The cross sectional shape of the individual mould units, and the manner in which they are supported in the cage along the longitudinal bars 11 permits free expansion and contraction during the heating and cooling stages, the outwardly divergent side walls of the mould units supporting the individual units against the next adjacent units, and the longitudinally extending entrance slots, permitting the strain of the circumferential expansion movement to be taken up entirely within the individual mould unit without any tendency to distort or crack within itself or to exert distorting or cracking force upon the adjacent mould units. The substantially uniform thickness of the outer walls of the mould units, and their relatively large ex-

posed surface conforming to the cross sectional shape of the mould cavity, assures effective and uniform cooling, so that the mould walls will not retain heat in excess of the critical temperature of the metal.

The dross or impure metal will be segregated in the flange formation disposed in the entrance slot, and as shown in Figs. 12 to 15 this flange 40 may be readily removed from the centrifugally cast body 41, so that the latter is in the form of a predetermined cross-sectional bar entirely free from impurities, and with a minimum waste of metal from the removal of the impure metal. Upon cooling the cast bars may be readily removed, either by removing the individual moulds from the cage, or by driving the bars from the moulds while the latter remain in the cage, the end plates being removed for this purpose and a suitable forcing tool being applied to the small ends of the bars to force them longitudinally from the divergent ends of the tapered mould cavities.

In Fig. 16 there is illustrated a mould assembly in which the individual moulds are of different cross sectional shape to produce a variety of shapes of bars. These are identified by the letters A to H, the mould A being a circular cross-section mould, similar to those illustrated in Figs. 1 to 15, the mould B being hexagon, mould C octagon, the mould D square with chamfered corners, the mould E square, the mould F pointed square, the mould G half hexagon, and the mould H half round. In the case of the mould units A, B, C and D, which have a contracted entrance slot, the mould units are preferably split to facilitate the removal of the moulded pieces, while in the case of the mould units E, F, G and H, which each have slightly divergent side walls and an entrance opening formed by the inner ends of these side walls, the mould units are preferably one-piece form. In each case the cooperative side surfaces of the several mould units and their engaging relation with the bars 11 are identical, so that it is possible in one assembly to include any number of the individual shapes, or, as in the arrangement illustrated in Figs. 1 to 15, to provide a complete assembly of any one of the several shapes.

I have illustrated and described a preferred and satisfactory embodiment of the invention, but it will be understood that changes may be made therein, within the spirit and scope thereof, as defined in the appended claims.

What is claimed is:

1. In a centrifugal casting machine, a mould carrier adapted for rotation about a longitudinal axis including a series of circumferentially spaced mould support members extending longitudinally in substantially parallel alignment with said axis, there being open spaces between said mould support members extending longitudinally in substantially parallel alignment with said axis, and a plurality of longitudinally disposed mould units carried within said carrier in concentric relation about and in parallel alignment with said axis, respectively disposed in said longitudinal spaces of said carrier and each supported along its longitudinal edge portions by said mould supporting members.

2. In a centrifugal casting machine, a mould carrier adapted for rotation about a longitudinal axis including a series of circumferentially spaced mould support members extending longitudinally in substantially parallel alignment with said axis and disposed in planes radial to said axis, there being open spaces between said mould support

members extending longitudinally in substantially parallel alignment with said axis, and a plurality of longitudinally disposed mould units carried within said carrier in concentric relation about and in parallel alignment with said axis, respectively disposed in said longitudinal spaces of said carrier and each supported along its longitudinal edge portions by said mould supporting members.

3. In a centrifugal casting machine, a mould carrier adapted for rotation about a longitudinal axis including a series of circumferentially spaced mould support members extending longitudinally in substantially parallel alignment with said axis and having longitudinally tapered mould support inner surfaces, there being open spaces between said mould support members extending longitudinally in substantially parallel alignment with said axis, and a plurality of longitudinally disposed mould units carried within said carrier in concentric relation about and in parallel alignment with said axis, respectively disposed in said longitudinal spaces of said carrier and each having longitudinally tapered shoulder ledge surfaces along its longitudinal edge portions engaged with said tapered surfaces of said mould supporting members.

4. In a centrifugal casting machine, a mould carrier adapted for rotation about a longitudinal axis including longitudinally spaced track ring members concentric to said axis and a series of circumferentially spaced mould support members extending longitudinally in substantially parallel alignment with said axis and secured to the inner peripheries of said ring members, there being open spaces between said mould support members extending longitudinally in substantially parallel alignment with said axis, and a plurality of longitudinally disposed mould units carried within said carrier in concentric relation about and in parallel alignment with said axis, respectively disposed in said longitudinal spaces of said carrier and each supported along its longitudinal edge portions by said mould supporting members.

5. In a centrifugal casting machine, a mould carrier adapted for rotation about a longitudinal axis including longitudinally spaced track ring members concentric to said axis and a series of circumferentially spaced mould support members extending longitudinally in substantially parallel alignment with said axis and secured to the inner peripheries of said ring members, there being open spaces between said mould support members extending longitudinally in substantially parallel alignment with said axis, a power unit including drive pulley wheels engaging and supporting said track ring members, and a plurality of longitudinally disposed mould units carried within said carrier in concentric relation about and in parallel alignment with said axis, respectively disposed in said longitudinal spaces of said carrier and each supported along its longitudinal edge portions by said mould supporting members.

6. In a centrifugal casting machine, a mould carrier adapted for rotation about a longitudinal axis including longitudinally spaced track ring members concentric to said axis and a series of circumferentially spaced mould support members extending longitudinally in substantially parallel alignment with said axis and secured to the inner peripheries of said ring members, there being open spaces between said mould support members extending longitudinally in substantially parallel alignment with said axis, a power unit including a plurality of pulley wheels engaged with said track rings at equally spaced points disposed

in radial planes of said axis, and a plurality of longitudinally disposed mould units carried within said carrier in concentric relation about and in parallel alignment with said axis, respectively disposed in said longitudinal spaces of said carrier and each supported along its longitudinal edge portions by said mould supporting members.

7. In a centrifugal casting machine, a mould carrier adapted for rotation about a longitudinal axis including a series of circumferentially spaced mould support members extending longitudinally in substantially parallel alignment with said axis, there being open spaces between said mould support members extending longitudinally in substantially parallel alignment with said axis, a plurality of longitudinally disposed mould units carried within said carrier in concentric relation about and in parallel alignment with said axis, respectively disposed in said longitudinal spaces of said carrier and each supported along its longitudinal edge portions by said mould supporting members, each of said mould units having a mould cavity extending longitudinally in substantially parallel alignment with said axis enclosed at its outer side, and an entrance slot at its inner side extending longitudinally in substantially parallel alignment with said axis, the outer peripheral wall portions of said mould units substantially conforming to the form of said mould cavities and being projected outwardly in said longitudinal spaces.

8. In a centrifugal casting machine, a mould carrier adapted for rotation about a longitudinal axis including a series of circumferentially spaced mould support members extending longitudinally in substantially parallel alignment with said axis, there being open spaces between said mould support members extending longitudinally in substantially parallel alignment with said axis, a plurality of longitudinally disposed mould units carried within said carrier in concentric relation about and in parallel alignment with said axis, respectively disposed in said longitudinal spaces of said carrier and each supported along its longitudinal edge portions by said mould supporting members, each of said mould units having an open-ended mould cavity extending longitudinally in substantially parallel alignment with said axis enclosed at its outer side, and an entrance slot at its inner side extending longitudinally in substantially parallel alignment with said axis, and closure end plates secured upon the ends of said mould units to close the open ends of the mould cavities.

9. In a centrifugal casting machine, a mould carrier adapted for rotation about a longitudinal axis including a series of circumferentially spaced mould support members extending longitudinally in substantially parallel alignment with said axis, there being open spaces between said mould support members extending longitudinally in substantially parallel alignment with said axis, a plurality of longitudinally disposed mould units carried within said carrier in concentric relation about and in parallel alignment with said axis, respectively disposed in said longitudinal spaces of said carrier and each supported along its longitudinal edge portions by said mould supporting members, each of said mould units having an open-ended mould cavity extending longitudinally in substantially parallel alignment with said axis enclosed at its outer side, and an entrance slot at its inner side extending longitudinally in substantially parallel alignment with said axis, and closure end plates

secured upon the ends of said mould units to close the open ends of the mould cavities, each of said end plates being disposed outwardly of the ends of said mould supporting members in longitudinally opposed relation thereto.

10. In a centrifugal casting machine, a mould carrier adapted for rotation about a longitudinal axis including a series of circumferentially spaced mould support members extending longitudinally in substantially parallel alignment with said axis, there being open spaces between said mould support members extending longitudinally in substantially parallel alignment with said axis, a plurality of longitudinally disposed mould units carried within said carrier in concentric relation about and in parallel alignment with said axis, respectively disposed in said longitudinal spaces of said carrier and each supported along its longitudinal edge portions by said mould supporting members, each of said mould units having an open-ended mould cavity extending longitudinally in substantially parallel alignment with said axis enclosed at its outer side, and an entrance slot at its inner side extending longitudinally in substantially parallel alignment with said axis, and closure end plates secured upon the ends of said mould units to close the open ends of the mould cavities, and tie rods extending between said end plates and arranged between the side walls of said mould units.

11. In a centrifugal casting machine, a mould

carrier adapted for rotation about a longitudinal axis, and a plurality of longitudinally disposed mould units carried within said carrier in concentric relation about and in parallel alignment with said axis, each of said mould units comprising a segment of a substantially cylindrical mould assembly, and each having within it a mould cavity defined by its outer wall and its two side walls and extending longitudinally in substantially parallel alignment with said axis, and each having at its inner side in spaced radially opposed relation to said outer wall a centrally disposed entrance slot extending longitudinally in substantially parallel alignment with said axis, the external side surfaces of each of said mould units being in radial planes of said axis and abutting the external side surfaces of the adjacent units at the inner periphery of said cylindrical mould assembly and in circumferential line with said entrance slots, and the outer wall of each of said units between said external side surfaces being of substantially uniform thicknesses, and substantially conforming to the cross-sectional form of its respective mould cavity, said mould carrier comprising circumferentially spaced mould supporting means having spaces between them wherein said outer walls of the mould units are exposed to the surrounding air.

HARRY G. SPECHT.
